TYPEWRITING MACHINE

Walter T. Sagner, Wethersfield, Conn., assignor
to Underwood Elliott Fisher Company, New
York, N. Y., a corporation of Delaware

Application April 8, 1936, Serial No. 73,211

10 Claims. (Cl. 197—177)

This invention relates to tabulating mechanism for use in typewriters, in adding and bookkeeping machines and the like, and more particularly to tabulating mechanism for tabulating to decimal or denominational positions in a plurality of columns on a work-sheet.

An application of the present invention is to a machine for filling in both credits and debits on a work-sheet. Usually the debits or the credits are tabulated on a work-sheet as a group, and in tabulating in either group the keys, which column-position in either group, are grouped together in one row on a keyboard. This invention permits direct tabulating to the "credit" position by the single actuation of a key. Heretofore three tabulating operations have been required to reach the "credit" position, namely, once each after "description," "debit," and "claims," in a standard bookkeeping form. It is obvious that in a series of repetitious tabulating operations, three in number, during the rapid operation of a machine, there is a probability of error in counting the number and performing the operations so that tabulating to the "credit" position is not always the expected result but the machine is set in another column. Such errors cause delay and confusion.

The aim of the present improvements in decimal-tabulating machines is to obviate these difficulties and permit a direct single-operation tabulation to the "credit" position, and thereby to save time and fatigue and eliminate liability of error.

Moreover the improvements include a novel separate set of decimal tabulator keys for the "credit" position in the same row and these separate keys have a distinguishing characteristic such as the color red, the supplemental keys being easily accessible in the same or usual row of tabulating keys.

A feature of the present invention is the provision of tabulating means in which a key-operated counter-stop may intercept one group of carriage-mounted stops and by-pass another group of such stops; another feature is the provision of tabulating means in which one group of carriage mounted or column stops may intercept one group of key-operated counter-stops and by-pass another group of such counter-stops, and vice versa, the other group of key-operated counter-stops may intercept another group of carriage mounted or column stops and by-pass the former group of carriage mounted or column stops; another feature is the provision of tabulating means

in which both groups of key-operated counter-stops may be denominational or decimal stops; and another feature of the invention is the provision of means in which a column-stop of one group may be coincident with a column-stop of another group, or may be offset a single letter-space therefrom; another feature, in which the keys of one group of denominational stops differ in color from those of another group, and, further, all of the keys being in the same row, and the keys of one color being on one side of the row and the keys of the other color on the opposite side of the row. Still another feature of the invention is the provision of a dummy column-stop where there is coincidence with another offset column-stop in the machine.

Another feature of the invention is the provision of a plurality of rows of stops on the carriage, each row being offset with reference to the line of travel of the carriage and determining a separate group of column-positions on a work-sheet, and also being offset with reference to each other row of carriage-stops, and a plurality of keys, one group being connected with counter-stops that engage one row of column-stops, and another group being connected with counter-stops that engage another row of column-stops; and further the column-stops are offset transversely and the counter-stops being upwardly extending and column-stop engaging, some stops being rearward and other stops being forward for engaging the transversely offset column-stops respectively; and further the stops co-act with denominational decimal-stops for determining column-decimal-denominational positions on a work-sheet; and further the column-stops are adjustable to different type-space positions.

Another feature of the invention is the provision of two sets of tabulating keys in the keyboard, one set for selecting the columns for "debts" posting, while another set is for tabulating to the columns used for "credits" posting, whereby the operator is relieved of operating the tabulator-key more than once for the credit column.

Another feature of the invention is the provision of a plurality of sets of column-stops for mounting on a carriage scale-rack, the sets having depending stop-lugs forwardly and rearwardly offset with reference to each other; and further, the sets being offset individually along the scale-rack a predetermined number of letter-spaces; and further, one of the sets being on the true printing position, and still further, said last-

mentioned set being co-mounted with register-actuators in a bookkeeping machine.

Other features and advantages will hereinafter appear.

5 In the accompanying drawings,

Figure 1 is a perspective view with parts broken away.

Figure 2 is a plan view, indicating the connections between the denominational keys and their 10 movable stops.

Figure 3 is a plan view, similar to Figure 2, but in which the "1000" denominational stops, in both the "debits" row and in the "credits" row, are removed, permitting the combining of a "debits" 15 column-stop and a "credits" column-stop on the same tappet-unit by forming one as an extension of the other, and allowing the use of a laterally condensed work-sheet; the carriage having moved into the first decimal position at the right 20 of the point, in the "proof balance" column of the work-sheet shown.

Figure 4 is a plan view, showing an arrangement of movable denominational stops, which permits the use of the full row of denominational 25 stops shown in Figure 2, but the "credits" scale would be offset from the "debits" scale eight letter-spaces.

Figure 5 is a right side elevation, partly in section, the typewriter operating in the first or 30 "debit" column of a work-sheet, and the adding machine being indicated diagrammatically at the front.

Figure 6 is a right side elevation showing a 35 tappet-unit supporting a column-stop and its relationship to a movable denominational stop in the "debits" row, with three teeth on the rear for actuating the registers of the adding machine.

Figure 7 is a right side elevation showing a 40 tappet-unit supporting a column-stop and its relationship to a movable stop in the "credits" row, with no teeth or tappets for actuating the adding machine.

Figure 8 is a bottom view of a modified "debits" 45 column-stop tappet-unit having a "credits" column-stop lug secured thereon one letter-space to the left of the "debits" lug considered in the operative position.

Figure 9 is a right side elevation showing a 50 tappet-unit and its relationship to the two offset rows of denominational movable stops, this tappet-unit combining both a "credits" and a "debits" column-stop, as shown in Figure 3.

Figure 10 is a right side elevation, showing the 55 "debits" tappet-unit that is shown in Figure 2 as the third tappet-unit from the left, from which both tabulator-stop lugs have been removed, inasmuch as this tappet-unit is related to the "credit" column on a work-sheet and carries only 60 adding machine operating parts.

The embodiment of the invention is shown in a Hanson-type bookkeeping machine including a typewriter 21, which is superimposed on an adding-machine base 22 having registers 23, a 65 row of numeral-keys 24, and below them the usual rows of alphabetical keys 24a, which operate the key-levers 25 in slots 26 provided in a comb 27. Notches 28 at the tops of the rear ends of the levers 25 engage a transverse pivot-rod 29, and coil-springs 30 support the key-levers 25.

A crank-lever 31 is pivoted on a transverse rod 32, and has a pin-and-slot connection 33 with a key-lever 25. A pin 34 mounted on the 70 upper end of the crank-lever 31 engages a slot 75

35 in the lower end of a type-bar 36, which also carries a hook 37 which engages the usual segmental pivot-rod 38. A cam 39 on the type-bar 36 engages and actuates the segmental portion of a universal bar 40, which contacts and 5 actuates an escapement 41, which is mounted on the horizontal shaft 42 and which engages an escapement ratchet-wheel 43 to which a pinion 44 is secured. A rack 45 is mounted on arms 46 pivotally attached by pins 47 to the sides of a 10 carriage 48. The carriage rides on a front rail 49 and a rear rail 50. A platen 51 rotatable on a shaft 52 is turned by a handle 53. A type 54 is mounted on the upper end of the type-bar 36.

Above the row of numeral-keys 24 on the front 15 of the machine are two rows of decimal tabulator-keys, both rows together forming a single row of keys, the row on the left consisting of five decimal tabulator-keys 55 having white tops, and the row on the right consisting of five similar 20 decimal tabulator-keys 56 having red tops. The row of keys 55 having white tops on a green body is for positioning the machine for debit-columns, and the row of keys 56 at the right having red tops on a green body is for positioning 25 the machine in credit-columns on a work-sheet.

The tabulator-keys 55 and 56 are mounted on tabulator-key-levers 57 pivoted on a transverse rod 58, which is mounted on a bracket 59 fastened by screws 60 to the typewriter 21. Denominational stop-reeds 61, spaced apart at their lower ends at letter-space intervals, rest, one each, on the rear ends of the tabulator-key-levers 57, and are mounted in a bracket-housing 119, which is secured on the rear of the machine 35 by screws 120. The upward motion of the reeds 61 is limited by elongated vertical slots 62, which enclose a transverse locking rod 63, which is mounted in the bracket 119. Spacers 64 are spaced between the lower ends of the reeds 61, 40 and the upper ends of the reeds slide in an aperture in a plate 65, which forms the top of the bracket 119. The aperture of the plate has two opposed racks formed by angled notches 66, which have the same contour as the beveled sides 45 of top plates 67 of the reeds 61. Each reed 61 has a forwardly and upwardly turned arm 68 to which is secured a depending tension-spring 69, which may be tied to a cross-piece, not shown, which may connect forwardly-projecting ears 50 70 of the bracket 119, as shown in the patent to William F. Helmond, No. 1,858,447.

A universal bar 71 is formed as the front depending edge of a rock-plate 72 mounted on a rock-shaft 73, which is journaled in the side 55 walls of the bracket 119. The rock-shaft 73 and the rock-plate 72 are secured against relative rotation by screws 74. A rearwardly-extending arm 75, which is also fast on the rock-shaft 73, engages the rear end of a release lever 76, which 60 is pivoted on a transverse shaft 77 and carries at its forward end a roll 78 which, when the rear end of the release lever 76 is depressed, engages and lifts the rack 45 out of engagement with the escapement-pinion 44.

65 It is clear, therefore, that when the decimal tabulator-keys 55 or 56 are depressed, the carriage is simultaneously released from the escapement 41. Forwardly of each numerical key-lever 25 an indexing link 79 is mounted on a 70 pivot-pin 80 and is connected with mechanism of the adding machine which is not shown.

A spring-drum 81 fast on the typewriter 21 furnishes power to move the carriage 48 by means of a strap 82 connected with the carriage 48. 75

- One of the utilities of the improvements is the facile imprinting of a work-sheet 83, which has the usual ledger-form for statements of account, and, as shown, comprises a column at the left headed "description", and six columns to the right headed "debit," "claims," "credit," "balance," "proof bal." and "old bal." This work-sheet form is widely used, but sometimes a change is made in the heading of the "claims" column.
- 10 In Figure 3, a modification has a work-sheet 83^a having the same forms as shown in Figure 2, but laterally condensed, the details of the modifications being hereinafter more fully explained.

A pair of rearwardly-extending brackets 84 are secured by bolts 85 and support a rack-bar 86, which is secured at both ends to the brackets 84 by means of screws 87. The rack-bar 86 has on the bottom surface a rack 88, and on the top surface a longitudinal V-groove 89. To the rear of the rack-bar 86 is mounted a scale 90 secured by screw-studs 91 at the rear ends of the brackets 84. The scale 90 consists of two separate scales, a "debits" scale 92 at the top and a "credits" scale 93 at the bottom. The scale 90 is adjustable for accurate alignment by elongated slots 94. The "credits" scale 93 is, as shown in Figure 2, six letter-spaces to the right of the "debits" scale 92, but the "debits" scale 92 is truly aligned with the printing position on the work-sheet.

36 The relationship of the offsetting, of the "credits" scale with reference to the "debits" scale, to the positions of the decimal tabulator-stops 101, 102, will be explained hereinafter.

A secondary bracket 95 is supported on the top of the bracket-housing 119 and projects rearwardly therefrom to form a housing 96, the rear upper wall of which forms a horizontal forwardly-extending flange 97.

40 A transverse row of slots 98 in the plate 65 guides vertically movable denomination bevel-top jacks 99, by means of which the register-bars of the adding machine are selected for indexing as a carriage-tappet 114 traverses said jacks. In the housing 96 are four cams 100 three of which are register-selecting cams, and the other is a subtraction-setting cam. "Debits" denominational stops 101 are mounted in one row on top of reeds 61 and are actuated by the "debits" row of denominational stop-keys 55. "Credits" denominational stops 102 are mounted in a parallel but offset row on top of reeds 61 and are actuated by the "credits" row of denominational stop-keys 56. All of the stops 101, 102 of both rows are beveled at the top on the right side for a purpose which will be hereinafter described.

55 A trip 103 for the operation of the cycling mechanism of the adding machine is mounted on the rear wall of the bracket-housing 119.

60 Tappet-units 104 have the common characteristic of three parallel teeth 105 on the top front end for engaging and supporting the tappet-units on the rack-bar 86, a leaf-spring 106 secured on the tappet-unit and having at its forward end a depending V-bend 107 for engaging the V-groove 89 in the top of the rack-bar 86, the teeth 105 and the spring 106 co-operating to secure the tappet-unit 104 in any set position on the rack-bar 86, a horizontal slot 108 in the rear end for engaging the flange 97, transverse vertical slots 109 in the bottom at the rear, and a centering line 110 for precisely setting the tappet-units 104 with reference to the scales 92 and 93.

75 The tappet-units 104 may be broadly divided

into two groups, a "debits" group and a "credits" group, the "debits" group carrying at the forward ends depending column-stops 111 which engage denominational stops 101 when the white-topped "debits" row of the denominational keys 55 is actuated, and the "credits" tappet-units 104 carrying, set back from the front ends, column-stops 112 which engage the "credits" denominational stops 102 when the red-topped "credits" row of denominational keys 56 is actuated.

All of the "debits" column-stops 111 are centrally positioned on the front ends of the "debits" tappet-units 104, and are coincidentally aligned with the lines at which "debits" tappet-units are set under the "debits" letter-space scale 92, which, in turn, corresponds with the letter-spaces as imprinted on the work-sheet 83, a total of eighty-six letter-spaces being provided.

In a modification shown in Figures 3 and 9, a "credits" column-stop 112 is also positioned on a "debits" tappet-unit 104 immediately behind and therefore continuous with the "debits" column-stop 111, and in a modification shown in Figure 8, a "credits" column-stop 112 is mounted on a "debits" tappet-unit 104, but is offset one letter-space and to the left when considered operatively in situ.

It will be noted in Figures 1 and 2 that any denominational key 56 in the "credits" row engages a stop 102 that is exactly six letter-spaces to the right of the corresponding denominational stop 101 that is actuated by one of the keys 55 in the "debits" row, that corresponds in column position to the "credits" key. The dot-and-dash lines in Figure 2 connect the keys 55, 56 with the controlled stops 101, 102. It is noted that the "credits" key marked "¢" is in the fifth space from the left of the "debits" key marked "¢," but a study of the stops 101, 102 shows a vacant letter-space to the right of the first "debits" stop 40 at the left, so that the "credits" stop 102 actuated by the "credits" key "¢" is six, not five, letter-spaces to the right of the "debits" stop 101 actuated by the "debits" key "¢." In other words, each "credits" denominational stop 102 is exactly 45 six letter-spaces to the right of the corresponding printing point on the work-sheet 83. It is obvious, therefore, that the "credits" column-stops 111 must be set on the letter-space scale exactly six letter-spaces to the right of the true 50 letter-space scale, and each "credits" tappet-unit 104 is set therefore six letter-spaces to the right of each "debits" tappet-unit 104 in the embodiment shown in Figure 2. For facility in setting the tappet-units in position to adapt the 55 device to work-sheets, which may have different letter-space requirements, a double scale 90 is used, the upper scale 92 showing the true letter-space position for positioning the "debits" column-stops 112, and the lower scale 93 showing letter-space positions exactly six letter-spaces to the right for positioning the "credits" column-stops 111.

Inasmuch as the "debits" tappet-units are the only ones at the true letter-space positions, in order to utilize the adding machine operators of a Hanson-type bookkeeping machine, it is necessary that all adding-machine tappet-actuators be aligned with the letter-space of imprint on a work-sheet, so therefore the offset "credits" 65 tappet-units are useless for this purpose, and only the "debits" tappet-units 104 may be used. The following adding machine actuating parts are mounted on each "debits" tappet-unit 104.

Fast on the side of each tappet-unit 104 is a 75

depending lug 113 which engages the adding machine cycling mechanism trip 103. The beveled denominational selecting tappet 114 is centrally positioned on the bottom of the tappet-unit 104, and approximately at the line of print actuates the denomination beveled topjacks 99. Register-selecting camming teeth 115 may be secured in the vertical slots 109, one or more according to the desired operation of the adding machine, 10 which engage and actuate the register-selecting cams 100. To provide for subtraction, a camming tooth 116 may be provided in the slot 109 at the extreme right. The register-selecting cams 100 are slideable vertically in slots 117 provided within the housing 96.

In the machine shown in the drawings in Figures 1 and 2, five denominational stops permit the imprinting of numbers, or amounts, up to and including 999.99. This machine is adapted 20 to the work-sheet 83 which, as shown, is a usual ledger or statement form provided with six columns for receiving the imprinting of figures. At the left is a column headed "Description." In sequence, from left to right, the columns are 25 headed, respectively, "Debit," "Claims," "Credit," "Balance," "Proof bal.," and "Old bal." This form generally remains the same in principle, although a different heading for the second column is sometimes substituted for "Claims."

30 For the purpose of indicating the utility of this invention, it suffices to state that "debits" are usually imprinted on the left side of the work-sheet 83, and further are usually filled in consecutively, and that "credits" are usually im- 35 printed on the right side of the work-sheet 83 and are usually filled in consecutively as a group. The novel arrangement of a single row of decimal denominational stop-keys having two con- 40 stituent rows of decimal denominational stop- keys 55, one row at the left, having a distinguishing characteristic, in this case the color white, and one row of keys 56, at the right, having a distinguishing characteristic, in this case the color red, each row of keys actuating a row of 45 denominational stops, the stops of one row being offset with reference to the stops of the other row, one row of denominational stops engaging "debits" column-stops, and the other row of de- 50 nominational stops engaging "credits" column- stops, permits tabulating directly to the desired column, and, as a result of this improvement, the operator is relieved of tabulating more than once to reach a desired column, so that a sub- 55 stantial saving of effort, time, liability of error and work is effected in making up statements of account. The mechanism is complicated by the requirement of addition and subtraction com- 60 puting operations in preparing these statements of account. Since the "debits" column-stops 111 are the only ones truly aligned, the "credits" column-stops 112 being offset six letter-spaces to the right, the "debits" column-stops 111 must be placed on the same tappet-units 104 as the lugs 113, tappet 114, and teeth 115, 116 that ac- 65 tuate the addition and subtraction mechanism, indicated but not shown in the base of the book-keeping machine, and in relationship to the ad- dition and subtraction mechanism all of the "credits" column-stops 112 must be placed on 70 tappet-units 104 that are dummies in relation- ship to this mechanism, and, to produce action in the registering mechanism in a "credits" column, it is obviously necessary that the machine operators be carried by a directly related "deb- 75 its" tappet-unit 104. In the case of the third col-

umn from the left or the "credit" column, a "debits" column-stop 111 would not only be use- less, but also would be needlessly in the way; in this case a tappet-unit 104 is provided, in the third position from the left, that is a dummy as 5 a column-stop, but has a full set of machine operators.

A condition may arise as shown in Figure 3. This work-sheet 83^a requires accommodation for numerals or figures only up to and including 10 999.99, thereby permitting the removal of the "1000" denominational stops 101, 102, the lateral condensation of the columns, and the combining on a single tappet-unit 104 of the "credits" column-stop 112, shown at "60" on scale 93 in Figure 15 2, and the "debits" column-stop 111, shown at "70" on scale 92 in Figure 2. Another condition, as shown in Figure 8, may arise in which both a "credits" column-stop 112 and a "debits" column-stop 111 are combined on a single tap- 20 pet-unit 104, but are offset a single letter-space.

In Figure 4, two sets of decimal denominational stops 101, 102 are shown arranged with any stop in one set being offset eight notches or letter-spaces from the corresponding stop in another set. This arrangement permits of a lateral expansion of the work-sheet 83 shown in Figure 2, by an amount equal to two letter- 25 spaces between the columns, and provides a construction in which two additional denominational stops may be introduced without changing the number of notches 66 in the plate 65.

In Figure 2, the following condition of the machine is shown: The "credits" denominational key 56 has raised its "credits" denominational stop 102 into the path of the first "credits" column-stop 112, something less than, or approxi- 35 mately half, a letter-space in advance of the letter-space printing position, the finger of the operator has been released from the key and the stop 112 has dropped, thereby permitting the carriage to come to a stop though action of the escapement 41 at the printing point, which is the first letter-space to the right of the decimal point position, a type 54 being shown in the position of imprint. In Figure 3, a similar condition is shown.

In adjusting the tappet-units 104 for a given work-sheet 83, the "debits" tappet-units 104 may be first set on the rack 86 and then either "cred- 50 its" column-stop tappet-units 104, or combined column-stop tappet-units 104, as shown in Figures 8 and 9, are inserted.

As shown the bookkeeping machine provides for three registers for addition or subtraction. A 55 different number of registers may be used, if desired, two empty slots 109 being provided for register-selecting camming teeth 115.

To assure the operation of the machine without its jamming, the tops of the denominational 60 stops 101, 102 terminate in a sharp edge formed by beveling each stop on the right side, and the column-stops 111, 112 are also beveled on the left side. The tappet 114 may be beveled on both sides to form an edge, and the co-engaging de- 65 nominational jacks 99 are also beveled at the top on both sides.

Variations may be resorted to within the scope of the invention, and portions of the improvements may be used without others.

Having thus described my invention, I claim:

1. In a typewriter, an adding or a bookkeeping machine, or the like, having a reciprocatorily mounted carriage for supporting a work-sheet, a tabulator-mechanism including in combination, 75

- a set of fixed stops on the carriage, a set of selectively operable denomination-keys, a set of denominational stops controlled by said keys for releasing the carriage and for engaging said set of fixed stops, whereby the carriage may be stopped at any one of a set of predetermined column-denominational positions, a second set of fixed stops on the carriage, said second set of fixed stops being offset from the first set of fixed stops with reference to a line of movement of the carriage, a second set of selectively operable denomination-keys, and a second set of denominational stops controlled by said second set of denomination-keys for releasing the carriage and engaging, one at a time, said second set of fixed stops, whereby the carriage may move past the first set of predetermined column-denominational positions and the carriage may be stopped at one of the second set of column-denominational positions, the sets of denominational stops being arranged in sequence in the direction of carriage travel, the set of keys controlling the second set of denominational counter-stops being separately positioned from and of a color different from that of the other set of keys, one set of fixed stops as for determining debits-columns at the left of the work-sheet, and another set of fixed stops as for determining credits-columns at the right of the work-sheet.
2. In a machine of the character described having a carriage positionable differentially relatively to item-columns in different lines, such as debit and credit forms of lines on a work-sheet; a duplex denominational carriage-tabulating mechanism including, in combination, two sets of denominational stops, each set having substantially the same decimal order of denominations of stops, one set for debit forms and another set for credit forms, means mounting said denominational stops so that the one set thereof is alongside the other set thereof in the direction of carriage travel, each denominational stop having a carriage-stopping contact, the carriage-stopping contacts of one set being offset as a group, transversely of the direction of carriage travel, from the group of carriage-stopping contacts of the other set, two sets of denominational keys cooperative with said denominational stops, there being altogether as many keys as there are denominational stops in the two sets of the latter, and debit-form and credit-form column stops on the carriage arranged so that a debit-form-column stop coacts only with the set of denominational debit-stops, and a credit-form-column stop coacts only with the set of denominational credit-stops, one or the other set of keys being used for any line of the work-sheet, depending on whether said line is of debit-form or credit-form.
3. In a machine constructed according to claim 2, inclusive of two individual scales on the carriage, one scale for setting the debit-form-column stops and the other scale for setting the credit-form-column stops, the debit-form-column stops having indices pointing particularly to the debit-scale, and the credit-form-column stops having indices pointing particularly to the credit-scale whereby the set-up of said debit and credit column-stops may be readily analyzed.
4. A tabulating mechanism for use in typewriters, bookkeeping machines, or the like including, in combination, a series of decimal denominational stops related to a group of forms for debits posting on the left side of a work-sheet, another series of decimal denominational stops related to a group of forms for credits posting on the right side of the work-sheet, both series being side by side along a line of typing but spaced apart transversely to a line of typing, two sets of decimal-keys, one set for each series of denominational stops, stops on the carriage and co-operative with only the debits decimal denominational stops, other stops on the carriage and co-operative with only the credits decimal denominational stops, and a dual scale, having one scale offset from another scale the same number of letter-spaces as the series of decimal denominational stops for debits posting is offset along the line of typing from the series of decimal denominational stops for credits posting.
5. In a typewriter, an adding or a bookkeeping machine, or the like, having a reciprocatorily mounted carriage, a duplex zone-skipping decimal tabulator-mechanism including, in combination, a fixed stop on the carriage, a set of movable decimal stops, a set of decimal-column selecting keys for releasing the carriage and actuating said decimal stops to engage said fixed stop at any selected decimal point, whereby the carriage may be stopped at a certain selected decimal position in a selected column, a second fixed stop on the carriage, said second fixed stop being offset from the first fixed stop with reference to the line of movement of the carriage, a second set of movable decimal stops, and a second separate set of decimal keys for releasing the carriage and actuating the second set of decimal stops to engage said second fixed stop at a selected decimal position, whereby the carriage may be stopped at another and separate predetermined decimal position in a key-selected column, and the carriage may move without any of said second set of decimal stops intercepting said first fixed stop in any position, and without any of said first decimal stops intercepting said second fixed stop in any position.
6. In a typewriter, an adding or a bookkeeping machine, or the like, having a reciprocatorily mounted carriage, a zone-skipping tabulator-mechanism including in combination, a set of fixed column-stops on the carriage, a set of decimal stops, a set of decimal keys, one for each decimal stop, for releasing the carriage and for actuating said decimal stops to engage said set of fixed column-stops, whereby the carriage may be stopped decimal at any one of a set of predetermined item-column positions, a second set of fixed column-stops on the carriage, said second set of fixed column-stops being offset from the first set of fixed stops with reference to a line of movement of the carriage, a second set of decimal stops, and a second set of independently movable decimal keys, for releasing the carriage and actuating the second set of decimal stops to engage, one at a time, said second set of fixed stops, whereby the carriage may move idly past a first set of predetermined column-denominational positions and may be stopped at one of the second set of column-denominational positions, said sets of denominational stops being arranged in sequence in the direction of carriage travel.
7. In a typewriter, an adding or a bookkeeping machine, or the like, having a reciprocatorily mounted carriage, a zone-skipping tabulator-mechanism including, in combination, a set of downwardly extending fixed column-stops on the carriage, a set of upwardly extending decimal stops, a set of decimal keys, one for each

stop, for releasing the carriage and for actuating said decimal stops to engage said set of fixed stops, whereby the carriage may be stopped at any selected decimal position in any column, 5 a second set of fixed column-stops on the carriage, said second set of fixed column-stops being offset from the first set of fixed column-stops with reference to the line of movement of the carriage, a second set of decimal stops, 10 arranged in sequence with the first set of decimal stops in the direction of carriage travel, a separate set of decimal keys, one for each decimal stop, for releasing the carriage and actuating the second set of decimal stops to engage, 15 one at a time, said second set of fixed column-stops, the second set of column-stops being downwardly extending and the second set of column-stops being upwardly extending, whereby at a tabulating operation the carriage may move 20 idly past one zone of decimal stops but may be stopped by the selected decimal stop in the second zone.

8. In a typewriter, an adding or a bookkeeping machine, or the like, having a reciprocatorily 25 mounted carriage, a tabulator-mechanism including in combination two column-selecting sets of decimal-selecting keys, two rows of movable denominational decimal stops selectable by said keys, said rows of decimal stops being offset 30 from each other transversely of the direction of carriage travel, said rows being arranged in sequence in said direction, and two rows of column-stops on the carriage, each row of column-stops coating with a separate row of decimal stops, whereby one row may tabulate only 35 to a certain order of columns such as credit-columns on a work-sheet and another row may tabulate only to another order of columns such as debits-columns.

40 9. In a tabulating mechanism for a typing-machine carriage, a single row of decimal-denomination-spaced stop-blades, said row ar-

ranged to afford, side by side, two sets of decimal-stops, in that one set has its row of stop-ends offset, transversely of the carriage-path, from the laterally adjacent row of stop-ends of the other set, two sets of decimal-denomination-tabulating keys, one key set being operatively associated with one set of said stops and the other key set being operatively associated with the other set of said stops, a column-stop device on the carriage co-operable solely 10 with one set of said stop-ends, and another column-stop device on the carriage co-operable solely with the other set of stop-ends, whereby to tabulate the carriage decimaly in different 15 orders of column-reaching jumps relative to different lines of typing such a credit-column-including lines and debit-column-including lines, the order of column-reaching jumps depending on which decimal-key set and associate decimal-stops and column-stop device are used. 20

10. In a typewriter and in tabulating mechanism, in combination, a power-driven carriage, an escapement mechanism for controlling the letter-feed movement of the carriage, means for releasing the carriage from the escapement mechanism to permit the carriage to run from one column-position to another, a plurality of groups of denomination-stops, a plurality of offset column-stops on the carriage, one group of denomination-stops being associated with one 30 column-stop, another group of denomination-stops being associated with another column-stop which is offset, transversely of the carriage-travel direction, with reference to the first column-stop, a set of denominational keys for controlling one group of denomination-stops, and another set of denominational keys for controlling the other group of denomination-stops, both sets of keys being in the same row, and the groups of denomination-stops being arranged 35 in sequence in said carriage-travel direction. 40
